COFFEE MAKER

Robert R. Gibson, Reisterstown, Md., assignor to Corning
Glass Works, Corning, N.Y., a corporation of New
York

Filed Nov. 21, 1969, Ser. No. 20,221

Term of patent 14 years

Int. Cl. D7—04

U.S. Cl. D44—26

Fig. 1

Fig. 2

Fig. 3

Fig. 4

Fig. 5

FIG. 1 is a side elevational view of a coffee maker embodying my new design, with the opposite side being a mirror image.

FIG. 2 is a top plan view.

FIG. 3 is a front elevational view.

FIG. 4 is a rear elevational view.

FIG. 5 is a bottom plan view.

The characteristic feature of the design resides in the particular surface ornamentation shown.

I claim:

The ornamental design for a coffee maker, as shown and described.
